MIRIAM C. ACKER, OF NEW YORK, N. Y., ASSIGNOR TO ISABEY-PARIS, INC., OF NEW YORK, N. Y., A CORPORATION OF DELAWARE

DESIGN FOR A LIP-STICK HOLDER

Application filed August 26, 1929. Serial No. 32,549. Term of patent 7 years.

To all whom it may concern:

Be it known that I, MIRIAM C. ACKER, a citizen of the United States, residing in the city of New York, county and State of New York, have invented a new, original, and ornamental Design for a Lip-Stick Holder, of which the following is a specification, reference being had to the accompanying drawing, forming a part thereof.

In the drawing,
Fig. 1 is a front elevation showing my design,

Fig. 2 is a rear elevation, and
Fig. 3 is a top view thereof.

I claim:

The ornamental design for a lipstick holder substantially as shown.

MIRIAM C. ACKER.
